UNITED STATES PATENT OFFICE.

NICHOLAS S. FILLYA, OF NEW YORK, N. Y.

FASTENING DEVICE.

Application filed September 21, 1928. Serial No. 307,463.

My invention relates to a new and improved form of fastening device.

One of the objects of my invention is to provide a new and improved form of fastening device which can be used in connection with belts, hand bags, and for a variety of other purposes for which a simple and compact fastening device is desirable.

Another object of my invention is to provide a fastening device having a base plate provided with a locking post, and also having a hinged plate which is provided with latch means for securely but releasably connecting it to the said locking post.

Another object of my invention is to provide a device of this type in which the hinged plate is provided with a latch plate which is reliably but releasably held in position by spring means.

Other objects of my invention will be set forth in the following description and drawings which illustrate preferred embodiments thereof, it being understood that the above general statement of the objects of my invention is intended to generally explain the same and not to limit it in any manner.

Fig. 1 is a top view illustrating one embodiment of my invention.

Fig. 2 is an end view of the device shown in Fig. 1.

Fig. 3 is a sectional view on the line 3—3 of Fig. 1.

Fig. 4 is a sectional view on the line 4—4 of Fig. 3.

Fig. 5 is a sectional view on the line 5—5 of Fig. 4.

Fig. 6 is a plan view of the springy detent plate.

Fig. 7 is a top view of the locking plate.

Fig. 8 is a top view of a second embodiment of my invention.

Fig. 9 is an elevation partially in section on the line 9—9 of Fig. 8.

Fig. 10 is a sectional view on the line 10—10 of Fig. 8.

Fig. 11 is a sectional view partially in elevation on the line 11—11 of Fig. 10.

Fig. 12 is a sectional view on the line 12—12 of Fig. 10.

Fig. 13 is a top view of the locking plate.

Fig. 14 is a view similar to Fig. 10, showing how the device is unlocked.

Fig. 15 is a top view of a third embodiment of my invention.

Fig. 16 is an end view of the device shown in Fig. 15.

Fig. 17 is a sectional view on the line 17—17 of Fig. 15.

Fig. 18 is a sectional view on the line 18—18 of Fig. 17.

Fig. 19 is a sectional view showing the device with the top plate in the open position.

Fig. 20 is a sectional view on the line 20—20 of Fig. 17.

Fig. 21 is a plan view of the locking plate used in this embodiment.

The embodiment shown in Figs. 1-7 inclusive is constructed and is operated as follows:

A base plate 1 has a rear slot 2 and upwardly bent lugs 3. This base plate may be the top of one of the metal frame members of a lady's handbag or the like. A top plate 4 is provided with downwardly bent lugs 5, which are connected to the respective lugs 3 by means of pins 6. All the parts of the device are made of any suitable metal or other material and while the device is described as being in the horizontal position, for convenience, it is obvious that the operation thereof is independent of its position. This top plate 4 may be a pivoted U-shaped catch of the ordinary type which overlaps the frame members of a lady's handbag or the like, so that the bag cannot be opened until the plate 4 has been swung upwardly.

A locking post 7 is connected to the base plate 1 by means of a bottom rivet-like extension which passes through an opening in the base plate. The right-hand or front part of the locking post 7 is provided with a locking recess.

As shown in Fig. 5 the upper plate 4 is provided with bottom guide flanges 8 in which the flanges 10' of the locking plate 9 slide. As shown in Fig. 3 this locking plate 9 is provided with an upwardly bent front flange 10 which limits the rearward movement thereof. The locking plate 9 is provided with an opening 11 having a front locking edge. When this locking edge enters the locking recess of the post 7 the upper plate 4 is held in the position shown in Fig. 3. When the locking plate 9 is slid forwardly so that the edge of the opening 11 does not engage the locking recess of the post 7, then the upper plate 4 is free to turn.

As shown in Fig. 6 the springy detent plate 12 is provided with a slot 14 at the rear thereof which divides it into two spring

legs. One of these spring legs has a slot 17 which receives a pin 16 connected to the locking plate 9 so that the locking plate 9 can be assembled with the spring or detent plate 12, while permitting a limited movement of the detent plate 12 on the locking plate 9. The detent plate 12 is provided with enlargements 18 at the rear thereof and these enlargements 18 are provided with 10 downwardly bent lugs 15. When the locking plate 9 is pushed inwardly, these enlargements 18 spring outwardly or away from each other to engage the rear of the upper plate 4. The locking plate 9 is thus 15 prevented from being moved forwardly to an extent sufficient to release it from the locking recess of the post 7. It would not be departing from my invention to make the pin 16 fit snugly within the opening 17.

20 To open the fastening device it is merely necessary to press the lugs 15 towards each other and push the locking plate 9 until it is moved forwardly to an extent sufficient to release the recess of the post 7 from the 25 edge or wall of the opening 11. The top of the post 7 is preferably conical and projects into an opening in the upper plate 4. The top of the post 7 may project beyond this opening but it would not be departing from 30 my invention if the top of the post 7 was either flush with or below the top of the upper plate 4. Since the detent plate 12 fits between the raised side flanges 10 a very compact device is provided and the detent 35 plate 12 is held in position at all times between the locking plate 9 and the top plate 4.

The embodiment shown in Figs. 8-14 is constructed and operates as follows:

40 The base plate 1 and the locking post 7 have the construction previously described. The top plate 4 and the bottom plate 1 are provided with co-operating pintle lugs, which are connected to a continuous lateral 45 pintle 6', as shown in Fig. 9. A torsion spring 19 is mounted on the pintle 6'. This torsion spring 19 consists of two end portions connected by a continuous intermediate 50 plate 19'. The torsion spring 19 tends to turn the spring plate 4 into the upper or open position. The locking plate 9' has the configuration shown in Fig. 13 and it is provided with an opening 11 having an angular right-hand wall which 55 performs the same function as the straight line right-hand wall of the opening 11 illustrated in Fig. 7. The locking plate 9' is provided with raised flanges 24 and 24' which fit slidably within the guide extensions 8 of the top plate 4. As shown in Fig. 60 13 the locking plate 9' has its raised side flanges 24 and 24' interrupted by recesses 23 and 23'. A manipulating member 21 is provided with a T-head 22 which is adapted 65 to fit in the recesses 23 and 23'. The inter-

mediate springy part 19' of the spring 19 bears against the manipulating member 21 and normally holds it in the position shown in Fig. 10, so that the T-head 22 prevents the locking plate 9' from being moved forwardly to the released position. 70

The manipulating member 21 is provided with a tab 20 which is pivotally connected thereto. In order to release the locking plate 9' the tab 20 is forced downwardly, 75 thus tilting the member 21 until it is in the position shown in Fig. 14. The member 21 can now be pushed inwardly until the locking plate 9' is pushed into the dotted line 80 position indicated in Fig. 14, in which position it is inoperative, as it releases the locking post 7. As seen in Fig. 11, the member 21 projects through a slot in the rear wall of the cover plate 4. The embodiment shown in Figs. 15-20 is constructed 85 and operates as follows:

The base plate 1 is provided with a slotted locking post 7, as before described. An intermediate plate 22' is pivotally connected to the base plate 1 by means of a hinge pintle 23''. A spring 24'' is mounted upon the pintle 23'' to normally urge intermediate plate 22' away from the base plate 1. The intermediate plate 22' is provided with guide flanges 8', which guide the movement of the locking plate 25 provided with a locking opening 26''. The locking plate 25 is provided with raised flanges 30 which slide upon the flanges 8' of the intermediate plate 22. Likewise, the locking plate 25 is provided with a raised rear flange 25' which slides against the adjacent face of the intermediate plate 22'. As shown in Fig. 20 the spring 24'' comprises two end portions which are integral with an intermediate U-shaped portion 19'', this being the same as the construction shown in Fig. 9. The upwardly bent hook like end 25' of the locking plate 25 is adapted to engage the intermediate portion 19'' of the spring 24''. The hinge connection between the intermediate plate 22' and the bottom plate 1, is provided by means of spaced sleeves 26 and 27, and a similar intermediate sleeve which is located in the space between the end sections of the spring 24''. These three bearing sleeves are integral with the base plate 1. Hence, the intermediate bend 19'' of the spring 24'' permits a limited sliding movement of the locking plate 25 to release it from the post 7. 110 That is, the intermediate bend 19'' prevents the locking plate 25 from being pulled out too far although it permits the limited sliding movement thereof. The top plate 28 is pivotally connected to the locking plate 25 by means of a pintle 29. Said top plate 28 can be snapped into position as shown in Fig. 17 as it is made of resilient metal. In order to conveniently turn the top plate 28 to its open position, it is provided with re- 115 120 125 130

cesses 31 and 32. It is clear that when the top plate 28 has been swung into the position shown in Fig. 19, that it can be pulled forwardly until the locking plate 25 is pulled forwardly to an extent sufficient to release the recess of the post 7, from the straight line edge or wall of the opening 26^a. When the device has been fully opened, the position of the parts is indicated by the dotted 10 lines in Fig. 19.

I have shown preferred embodiments of my invention, but it is clear that numerous changes and omissions could be made without departing from its spirit.

15 I claim:

1. A fastening device comprising a base plate having a locking post, a second plate pivotally connected to said base plate and having longitudinal guide flanges and a 20 locking plate slidably located between said flanges and between said base plate and said second plate, said locking plate being adapted to engage the said post, said locking plate being movably connected to said second plate 25 so that it can be moved either to the operative or to the inoperative position.

2. A fastening device comprising a base plate having a locking post connected thereto, a second plate pivotally connected to 30 said base plate and having longitudinal guide flanges, said locking post having a locking recess formed therein, and a locking plate slidably located between said flanges and between said base plate and said second 35 plate, said locking plate having an opening through which the said post passes, a part of the wall of said opening being adapted to enter said locking recess to lock said second plate with respect to the base plate.

40 3. A fastening device comprising a base plate having a locking post connected thereto, a second plate pivotally connected to said base plate and having longitudinal guide flanges, said locking post having a locking 45 recess formed therein, and a locking plate slidably located between said flanges and

between said base plate and said second plate, said locking plate having an opening through which the said post passes, a part 50 of the wall of said opening being adapted to enter said locking recess to lock said second plate with respect to the base plate and actuating means connected to said locking plate, said actuating means being adapted to project beyond the said second plate. 55

4. A fastening device comprising a base plate having a locking post, a second plate pivotally connected to said base plate, a locking plate slidably connected to said second plate, said locking plate being adapted to engage the said post, actuating means connected to said locking plate, and adapted to project beyond the second plate, said actuating means being adapted to manipulate the said locking plate so that it can be 60 moved either to the operative or to the inoperative position, said actuating means being movable with respect to the second plate and being adapted in one of the positions thereof to hold the locking plate in operative 65 position.

5. A fastening device comprising a base plate having a locking post, a second plate pivotally connected to said base plate, a locking plate slidably connected to said second plate, said locking plate being adapted to engage the said post, actuating means connected to said locking plate, and adapted to project beyond the second plate, said actuating means being adapted to manipulate the said locking plate so that it can be moved 70 either to the operative or to the inoperative position, said actuating means being movable with respect to the second plate and being adapted in one of the positions thereof 75 to hold the locking plate in operative position. 80

In testimony whereof I affix my signature.

NICHOLAS S. FILLYA.
